(57) **CLAIM**

The ornamental design for a trolley apparatus for slackline webbing, as shown and described.

DESCRIPTION

FIG. 1 is a perspective view of the trolley apparatus for slackline webbing according to the new design;

FIG. 2 is a front view thereof;

FIG. 3 is a side view thereof;

FIG. 4 is a top view thereof; and

FIG. 5 is a bottom view thereof.

FIG. 6 is a perspective view of a second embodiment of the trolley apparatus for slackline webbing;

FIG. 7 is a front view thereof;

FIG. 8 is a side view thereof;

FIG. 9 is a top view thereof; and,

FIG. 10 is a bottom view thereof.

The broken lines depict portions of the structure that form no part of the claimed design.

1 Claim, 4 Drawing Sheets
